UNITED STATES PATENT OFFICE.

FRANCIS McGHAN, OF WASHINGTON, DISTRICT OF COLUMBIA.

WATER-CLOSET.

Specification of Letters Patent No. 19,375, dated February 16, 1858.

To all whom it may concern:

Be it known that I, FRANCIS McGHAN, of Washington city and District of Columbia, have invented a new and useful Improvement 5 in Water-Closets; and I do hereby declare that the following is a full, clear, and exact description of the construction and operation of the same, reference being had to the annexed drawing, forming part of 10 this specification, in which—

Figure 1 is a top view of closet with seat removed to show water apparatus. Fig. 2 is a front elevation with casing broken out. Fig. 3 is a section on lines $\alpha\alpha$ and $\gamma\gamma$.

15 Similar characters of reference in the several figures denote the same part.

The nature of my invention consists in a peculiar construction for regulating the flow of water to pan closets, for cleansing them 20 after use.

In the drawing B is the basin, P is the pan hung upon shaft a , and C is the waste chamber with discharge pipe leading therefrom. Water flows to the basin through the 25 pipe A, discharging therein at b (Fig. 3). The other mouth of this pipe is in plate c , against which the elastic diaphragm valve f acts. The head of water is conveyed through pipe I whose mouth is closed by the metallic 30 center of valve f , as shown in Fig. 3. Behind the rubber diaphragm of the valve is a metallic disk i of greater diameter than the center piece e against which the head of water acts to force back the valve and establish a flow through pipe A, to the basin. Behind the valve is a chamber D, entirely 35 closed except at top where the pipe m enters. This pipe is in communication with the waste chamber C, by channel n ; thus giving an outlet from chamber D into the waste chamber. This communication is 40 regulated by a valve v at the lower end of rod r , so that when the valve rests upon its seat, as shown in Fig. 3, the flow of water from 45 chamber D will be stopped. There is an elastic diaphragm packing p attached to the rod r and pipe m , to prevent water passing out the mouth of the pipe, and aid in returning the valve to its seat. The rod is attached to lever l , whose fulcrum is at g , and which by reason of weight w at the extremity of its long arm, has a tendency to keep valve v upon its seat, as shown in Fig. 2. Lever l is actuated by lever L, whose long 50 arm is lifted by power applied to handle h of rod g , the weight w at its extremity returning it to the position shown in Fig. 2 when this power is removed.

A stud s on long arm of lever L works in the slotted arm a' of shaft a , to tilt the pan 60 when the handle h is lifted. This lifting of the handle h is the ordinary operation after using pan closets. Its effect upon this construction is to discharge the contents of the pan, and permit a portion of the contents of 65 chamber D to be forced into the waste chamber C.

Through the center of the valve f is an aperture o , the size of which is regulated by a screw k , as seen in Fig. 3. The effect of this 70 opening is to furnish a gradual supply of water to chamber D, the time of filling which will depend on the size of the opening.

When the chamber D is filled with water, 75 there will exist a pressure of the full head through pipe I against the disk i , and since this disk is greater in diameter than plate e against which the direct pressure of the head of water is brought, the valve f is 80 forced against plate e , and the mouth of pipe I stopped by plug e .

This is the condition of the apparatus prior to use, immediately after which the handle h is lifted. This operation as above 85 stated, opens valve v simultaneously with the tilting of the pan, which permits the pressure against plate e to force back the elastic diaphragm f and permit the flow of water through pipe A to the basin, the 90 displaced contents of chamber D passing to waste chamber C. The handle h drops the instant the hand of the operator is withdrawn, restoring all parts to their proper condition, while the flow of water through 95 pipe A continues until sufficient water has passed through opening o to force the valve against plate e . This length of time depending on the dimensions of the said adjustable opening.

Having described my invention, what I claim and desire to secure by Letters Patent is—

The chamber D behind valve f in adjustable communication with the water head, 105 and having a waste discharge by the operation of the lever tilting the pan substantially as, and for the purpose set forth.

In testimony whereof, I have hereunto signed my name before two subscribing witnesses.

FRANCIS McGHAN.
